UNITED STATES PATENT OFFICE.

CHARLES P. HIDDEN, OF PROVIDENCE, RHODE ISLAND, ASSIGNOR TO NITROGEN PRODUCTS COMPANY, OF PROVIDENCE, RHODE ISLAND, A CORPORATION OF RHODE ISLAND.

PROCESS AND MEANS FOR PRODUCING METALLIC CYANIDS.

1,352,192.

Specification of Letters Patent.

Patented Sept. 7, 1920.

Application filed November 18, 1918. Serial No. 262,925.

To all whom it may concern:

Be it known that I, CHARLES P. HIDDEN, a citizen of the United States, residing at Providence, in the county of Providence and State of Rhode Island, have invented certain new and useful Improvements in Processes and Means for Producing Metallic Cyanids, of which the following is a specification.

10 This invention relates to a process and means for producing alkali metal cyanids and has for one of its objects the effecting of a nitrogen fixing reaction in which participate the nitrogen to be fixed, sodium carbonate or the like and carbon, in such manner that a more copious yield of the product resulting from such reaction, may be obtained.

In the patent to John E. Bucher, No. 26 1,120,682, dated December 15, 1914, there is described a process for producing cyanid through the intermediacy of such a reaction; the operation preferably being conducted continuously in a vertical retort or 25 the like.

In said Bucher process a preferred mode of conducting the operation involves forming an intimate mixture of finely divided iron, sodium carbonate and powdered coke, 30 for example, and then briquetting said mixture, in order that the charge treated in the retort may be sufficiently open in structure to permit of the free passage of nitrogen therethrough.

35 These briquets are themselves porous, so that the nitrogen current is thereby enabled to gain free access to the interiors thereof, and when said briquets have been heated to a reacting temperature, sodium cyanid, for 40 example, will be formed according to the equation:

45 As the herein described process, in one of its aspects constitutes an improvement upon said process of John E. Bucher, it will suffice, for present purposes, to direct the attention of those skilled in the art to the detailed disclosures set forth in the patent aforesaid, and in the earlier patent to said Bucher, No. 1,091,425, dated March 24, 1914.

Before proceeding further with the present discussion, reference will now be made to

the drawing which forms a part hereof; like 55 reference characters referring to like parts in the respective views. As I am aware of various changes which may be made in the process herein described and in the apparatus, given by way of exemplification, in 60 which said process may be effectuated, I desire to be limited only by the scope of the appended claims broadly interpreted in the light of my disclosure.

Referring to said drawing: 65
Figure 1 is a somewhat diagrammatic representation of a cyanizing furnace in which is a vertical retort, preferably consisting of three pipe sections.

Fig. 2 is a detail section taken on the line 70 II—II of Fig. 1.

The upper pipe section, 1, may conveniently be telescoped into the intermediate section 2, and the latter in turn into the lower or cooling section 3; the joints being 75 welded gas tight.

Brickwork 4 is disposed to provide a conduit 5 through which the heating gases are led into the retort chamber 6, and thence out via a flue 7, as per the arrows. 80

At the top of the section 1 is a hopper 8 through which the briquets 9 are fed into the retort; while a suitable feed mechanism in a casing 10 receives and removes from the cooling section 3, the material produced by 85 the cyanizing operation.

The specific construction of mechanism in the casing 10 does not concern the present invention and hence need not herein be further referred to. 90

The orifices in the brickwork through which the retort is introduced, are sealed substantially gas tight, as by kieselguhr 11 and slabs 12—13 of heat resistant material; while the lower end of the retort is sealed 95 gas tight into the mouth of the casing 10 by means of packing 14 and a packing ring 15.

The upper end of section 1 preferably extends up through and somewhat beyond the top of the furnace, and may be heat insulated, as at 16, for reasons hereinafter set forth. 100

Into the upper end of the retort is inserted a relatively small pipe 17, through which preheated carbon monoxid,—mixed 105 or unmixed with nitrogen, but preferably substantially pure,—is introduced into said upper end of the retort; pipe 17 being, de-

sirably, heat insulated, as at 17' to prevent chilling of this preheated gas.

Free nitrogen, preferably pure and reasonably preheated, is supplied to the bottom 5 of section 3 from the casing 10.

The retort is, in practice, continuously operated; gravity causing the briquets to feed downwardly therethrough, as the cyanized material at the bottom is withdrawn through 10 the casing 10; fresh material being, of course, supplied to the hopper 8, as needed, to maintain the section 1 substantially filled at all times.

If we assume that the mechanism in casing 15 10 is rendered inoperative, temporarily, then to all intents and purposes, the furnace will behave and may be regarded as a batch furnace; the reason for which consideration will now be pointed out.

It has been found as the result of experiment and observation, when using, for example, a vertical retort such as that described, whether such retort be operated continuously, or for the treatment of batches of 25 material, as in a batch furnace, that there is a tendency for the product to form in unequal amounts in successive zones, descending from the top; so that if, by way of illustration, the heated central portion of the retort 30 be divided for convenience into five theoretical zones, *a*, *b*, *c*, *d* and *e* (which of course would have no real lines or planes of demarkation therebetween),—then, in *a*, the first of these, at the top of the chamber 6, if 35 the direction of the nitrogen current be upward, there may, for example, be a formation of cyanid amounting to two or three per cent. of the total weight of the charge, after the latter has been cooled and analyzed to 40 ascertain its cyanid content.

Assuming that the briquet mixture is initially uniform in each of the five zones, and that the briquets in said retort, operating as in a batch furnace, have been subjected to the 45 action of the ascending current of nitrogen, at a temperature of approximately 1060 to 1090° C., as is to be preferred; then while perhaps two per cent. of cyanid may have been formed in zone *a*, we would find possibly 50 eight or nine per cent. in the next lower zone, *b*; possibly fifteen per cent. in the third zone, *c*; and, for example, thirty per cent. or more in the next lower zone, *d*.

In the bottom zone *e*, it is noteworthy, 55 that in such a batch furnace, one finds, usually, that the percentage content of cyanid has not further increased; but on the contrary has materially diminished. Therefore, while we may have had thirty or thirty-five per cent. of cyanid in zone *d*, we find anywhere from twenty per cent. to eight or ten, or even none, for example, in zone *e*.

This upon first consideration would seem 60 to be rather surprising; because the mixture in each of these zones was initially identical.

and only pure nitrogen has been passed up through the charge; other than the carbon monoxid formed during the course of the reaction in the retort.

From the fact that in a batch furnace, 70 after the cyanizing operation has been completed, one finds, just above the zone *a*, a layer of sodium carbonate, which is, of course, upon and in the pores of the briquets at this point,—coupled with the fact that in zone *a* there is usually a considerable excess of sodium carbonate in the briquets, over their normal or initial content of this material; while in zone *b*, there is, frequently, 75 still an excess of this substance, but less pronounced, etc.,—indicates that some action is occurring in the retort analogous in its effect to a distillation of the alkali metal carbonate.

I have been of the opinion and have recently been confirmed in this, that sodium 85 cyanid, for example volatilizes at a temperature materially below that at which sodium carbonate vaporizes or decomposes; and that at a temperature of, say, 1060° C., it is hence principally alkali metal in the 90 form of cyanid rather than of carbonate which thus migrates through the reacting mass. It is for this reason that the action in the retort was above referred to as "analogous" in its effect to a distillation of the 95 alkali metal carbonate.

This distinction is of importance, because if it was primarily or principally sodium carbonate which traveled, as such, in gaseous form from the lower zones toward the upper 100 in the reaction chamber or space of the retort, then, what is now to be described would be in large measure without effect.

To begin with, sodium cyanid, at a temperature even as low as 600° C., or somewhat 105 lower,—reacts with carbon monoxid, especially when in the presence of material such as catalytic briquets of the type herein-referred to; the reaction probably, being according to the following equation:

An inspection of equation 1, will show that equation 2 is the reverse thereof.

The direction of this reversible reaction is hence primarily dependent upon temperature and, secondarily, it is dependent upon the relative masses of cyanid, carbon monoxid and carbonate present in the same zone 115 or locality.

Now, carbon monoxid is formed whenever and wherever the cyanid is formed in the retort, but on account of the preferably ascending current of nitrogen in said retort, this gaseous by-product is wafted toward the upper zones and, hence is most concentrated in zone *a*. The temperature of the charge in zone *a*, is, however, lower than that in *b*, and as a result, normally, little or no cyanid 125

tends to form in zone *a* in the presence of its high content of CO, while much of the cyanid which volatilizes in lower zones and ascends as far as zone *a*, is, indeed, reconverted back to carbonate.

Any cyanid which happens to pass unchanged through zone *a*, is in any case promptly converted to carbonate at the base of the column of relatively cool briquets immediately thereabove, where the temperature is much lower and hence favorable to the reaction as per equation 2. This is proven by the formation of the crust of sodium carbonate just above zone *a*, in the batch furnace operation.

Now, since the cyanid tends to more or less slowly volatilize from all of the zones, *a*, *b*, *c*, etc., and especially from the hotter ones, it is evident that in such hotter zones it will volatilize most rapidly when its vapor pressure is lowest. This is, of course, in the bottom zone *e*, since while this is slightly cooler than zone *d*, the latter receives vaporous cyanid from *e*, which tends to prevent excessive volatilization from *d* until *e* has been largely exhausted of cyanid, after which *d* will become the zone from which migration of the alkali metal in the form of its cyanid, will most copiously occur; and so on.

In other words, if, a charge such as that in question, be treated long enough in a batch furnace, it is possible to remove practically all alkali metal from zones *b*, *c*, *d* and *e*, and especially from *e* and *d*.

Without the alkali metal, its cyanid cannot be formed; and, if it is thus removed from the points where it is most urgently needed in a continuous furnace of the class described, if a copious yield of cyanid is to be afforded in the cooling section 3 of the retort, a problem is presented as to how best to conserve a high content of this metal in zone *e*.

If the initial alkali content of the briquets supplied to hopper 8, be too high, then they tend to choke the retort when the latter is operated as in a continuous furnace; this choking or sticking commonly occurring near the entrance to zone *a*, which is where the alkali content will be highest as a result of the reformation and deposition of the carbonate at this point, as above described,—this so deposited carbonate sup-

plementing that already in the briquets. Again, if the rate of feed of the charge through the retort be made excessive, in order to carry alkali metal down to zone *e* copiously, then (in the absence of heating provisions such as those hereinafter described, or the equivalent thereof), unless the retort be of small diameter, which is obviously objectionable commercially, the charge, which is a poor conductor of heat, will not all be properly heated by the time

it reaches zone *d* and the cyanid yield will be correspondingly diminished; while if the temperature of the furnace be raised, to overcome this, then, in such case, the retort will have to be subjected to this higher temperature and its life will be correspondingly shortened, etc.

The ideal condition is to have the descending briquets well and uniformly heated either up to reaction temperature by the time that they reach zone *d*, or a point within this zone, while substantially preventing cyanid formation before this point is reached,—or, while said briquets are traveling toward this point, to preheat them quite uniformly almost but not quite up to the temperature required for the reaction to occur vigorously as per equation 1, while preserving around them and especially in their pores, an atmosphere having a relatively high CO content resulting from the cyanid forming reaction therebelow; and then, in the case where they are already at reaction temperature by the time said point is reached, to promptly remove the influence which prevents the formation of cyanid, to permit such formation to take place vigorously; or, in the case where the temperature was insufficiently high, to promptly raise this temperature to the degree necessary for copious cyanid formation, while at the same time changing the atmosphere about and in the briquets, to supply one of nearly pure nitrogen having a greatly reduced CO content.

In other words, while, in the first instance, the briquets are at a temperature such that in the absence of the preventing influence, cyanid formation would occur, in the second instance they are insufficiently heated in an atmosphere having but a moderately high CO content, and since the preferred preventing influence in question is an atmosphere having a decidedly high CO content, the principle in each case is much the same; this principle, of course, involving the countering, as it were, of the effect of higher or lower temperature, by, respectively, greater or less concentrations of carbon monoxid.

That is to say, I, preferably, either have but a normal development of CO in the upper zones, *a* and *b* especially, and hold down the temperature while nevertheless thoroughly and uniformly heating the charge at such time; or, I supply an atmosphere particularly high in CO, and depend upon this to blanket down the reaction, so to speak, in spite of the presence of a temperature sufficiently high to normally yield cyanid copiously.

I may also use a combination of these two applications of the principle in question, by not only supplying, or causing to form, an atmosphere having a quite high CO content,

but also effecting the indicated heat changes in the different zones of the retort.

Where a very high carbon monoxid concentration in the upper part of the retort is desired, this can conveniently be accomplished by piping in hot CO through the pipe 17, to supplement that already present in zones *a* and *b*. The velocity of this entering gas is sufficient to project it well down into the retort before it is finally reversed in direction of flow, by the gases ascending toward the hopper 8.

The temperature regulation may be simply and conveniently effected by providing, for example, a deflecting wall 4' against which impinge the heating gases traversing the conduit 5; the septum 4" separating conduit 5 from the chamber 6, being preferably cut away or shaped as shown, to cause the gaseous current to pass principally over and around that portion of the retort defined by zones *d* and *e*.

The result of this disposition of the gaseous heating current, is to cause zones *b* and *c*, and especially the latter, to heat up quite uniformly almost, but not quite, to the desired reaction temperature attained in zone *d*, especially in the lower part of this zone, and in the upper part of zone *e*.

The nitrogen flowing up through the cooling section 3, becomes highly preheated in so doing, while, of course, the descending briquets in this section are correspondingly cooled, preparatory to removal; and this current of hot nitrogen should be sufficiently strong to permeate the porous briquets and sweep out the remaining carbon monoxid carried down in their pores from zones *a* and *b* into zone *c*. This entrained carbon monoxid, by the way, prevents any very copious formation of cyanid in zone *c*.

As cyanid is largely prevented from forming in the upper part of the heat chamber of the retort, the alkali metal content of the briquets herein, is preserved in the form of alkali metal carbonate. Also, since the re-formation of this carbonate near the entrance to zone *a* is largely prevented,—I am able to feed through the retort, briquets having a considerably higher alkali metal content, with even less tendency to choke than in the case of briquets having a lower initial carbonate content, where this migration of alkali metal in the form of cyanid, is not thus restricted.

Of course, some volatilization of cyanid will occur in zones *d* and *e*; but the amount of this is relatively small, compared to that which occurs when cyanid is permitted to form copiously throughout zones *b*, *c*, *d* and *e*,—while, on account of the downward movement of the charge, when operating as herein described, even the alkali metal of the cyanid which thus migrates from zones *e* and *d*, is quite promptly returned to zone

d (and thereafter to zone *e*), following the reconversion of such cyanid to carbonate in the CO laden zones above.

A further advantage resides in thus introducing carbon monoxid gas into the upper zones to supplement the CO formed during the cyanid producing reaction in the lower zone or zones, since, as described in said Bucher Patent No. 1,120,682, the following reaction occurs within the mass of briquets feeding down through the upper end of the retort:

Thus an additional amount of carbon is deposited in especially desirable form, together with a liberation of heat, directly in the pores of the briquets being introduced into the highly heated portion of the retort.

In Fig. 5 of said Bucher Patent, No. 1,120,682, a means for thus introducing carbon monoxid at the top of the retort is shown; but no provision is shown or described for simultaneously introducing nitrogen, substantially free from carbon monoxid, at the lower end of the retort, whereby to sweep away the CO entrained in the descending briquets,—which is obviously most desirable in view of the foregoing.

By thus simultaneously introducing nitrogen at one end of the retort and carbon monoxid at the other, as described, I therefore preserve the advantage of obtaining additional carbon for the briquets, with the added advantage that this additional amount of CO is enabled to coact with the nitrogen current to afford a greater yield of cyanid.

If some carbon dioxide is present in the supply of CO, introduced through the pipe 17, it will, of course, tend to hasten the oxidation of any cyanid in zone *a*, or in the portion of the retort immediately thereabove,—with consequent formation of the carbonate at this point; but this is of no advantage, since such cyanid is in any case converted into carbonate; while, further, since it is desired to effect a conversion of CO into CO₂, in the space above zone *a*, the presence of this CO₂ is objectionable as tending to retard such conversion to whatever extent the CO₂ may be present.

To favor the deposition of carbon in the incoming briquets, I prefer to, in effect, prolong that portion of the retort which lies above the zone *a*, and in order that the temperature in this section may not fall too low, which would prevent the desired conversion of CO to CO₂, I insulate this part of the retort, as at 16, etc., to the end that the briquets in the hopper 8, or its equivalent, may be maintained at, for example, 550° C.

If desired, the hopper may be provided with a removable cover 18, to which may be

permanently connected that part of the pipe 17 which projects down into section 1 of the retort. The upper part of the pipe is preferably separably connected to this cover, as 5 is also a closed chute 19, to permit of vertical withdrawal of said cover.

Chute 19, forms in effect, an extension of the retort, so that a further deposition of carbon may be effected therein; but it possesses an advantage over a long vertical extension, in that while the briquets to be 10 cyanized may pass freely down therethrough, the inclination of the chute or conduit is such as to relieve the plastic mass 15 of briquets in zones *a*, *b*, etc., from the head or pressure that they would otherwise be subjected to were the chute vertical; while at the same time any necessity for providing moving conveying parts in contact with 20 the hot ascending gases, is eliminated.

I especially wish to direct attention to the variations in temperature in the different zones *a*, *b*, etc., which is so conveniently effected in the simple manner shown. The 25 effect upon the success of the process, of this provision of a highly heated portion of the retort just above the cooling section 3, together with a more moderately heated portion substantially immediately there- 30 above, is so potent, for reasons hereinbefore set forth, that with it alone and without the provision of the supplementary current of carbon monoxid in the upper zone or zones, it is still possible to work the retort 35 to advantage. The introduction of additional CO into zone *a*, however, permits of heating zones *a* and *b* to a somewhat higher temperature than when the pipe 17 is not used, in the fashion described, with the re- 40 sult that the total length of the retort exposed to the action of the heating gases in chamber 6, may be correspondingly re- 45duced. This favors uniform feeding of the charge and saves retort cost, which in case the entire retort is of iron, amounts to con- siderable in time, by reason of the occasional necessary replacements.

I prefer to form the section 2, which is exposed to the more intense heat, of a suitable 50 heat resistant alloy, such as one of nickel, iron and chromium, or the like.

The larger diameter cooling section receives the lower end of the alloy section 2, and is welded securely thereto; while I preferably make section 1 of iron, to save expense, and likewise am able to telescope and weld its lower end into the upper end of section 2 which is correspondingly larger in diameter than section 1.

Another advantage resides in making retort section 1 of less diameter than section 2, since the upward current of gas traversing zones *c*, *b* and *a* is thereby rendered more rapid than the current of said gas in 60 zones *e* and *d*.

The effect of this is, that the inflowing nitrogen passing through zones *e* and *d*, does not tend to sweep upward the vaporous cyanid in said zones, which would increase the undesired volatilization therefrom, as 70 much as would a nitrogen current of increased velocity; while, on the other hand, the more rapid gaseous current passing through zone *c*, rapidly sweeps out the carbon monoxid entrained in the pores of the 75 briquets descending from zones *a* and *b*.

Finally, I desire to emphasize the importance of having the hottest part of the retort as near as possible to the cooling section 3, since it is at this point that cyanid 80 formation, under the prescribed conditions, can occur most copiously, and before such cyanid has become volatilized to any very material extent, it drops down with the other non-gaseous reaction residues, into the 85 cooling section where, as its temperature is promptly lowered, further volatilization becomes impossible.

To favor this local heating, especially when section 2 is formed of such a heat re- 90 sistant alloy as that described, convergent apertures 20-20' may be provided in the septum 4", so as to allow a part of the heating gases to pass directly through said wall, preferably at a plurality of points, to per- 95 mit of impingement of said gases practically against three sides, at least, of the section 2.

The inner wall of this septum may also be somewhat laterally arched or coned, as shown, to effect a concentration upon section 100 2 of the heating gas descending from the wall 4'.

In general, therefore, it will be noted that I have exemplified a plurality of means and modes of procedure for retarding the 105 formation of cyanid in or near the end of the externally heated portion of a continuously operating retort, from which the reaction gases emerge, while especially favoring said formation in a reaction zone of but limited extent compared to the total length of said heated portion, such reaction zone being quite closely adjacent to the cooling section. In the preferred apparatus and mode of conducting the process, these means and 110 steps are advantageously combined to secure economies of apparatus and fuel, as well as increased yield of the product sought.

Having thus described my invention, what I claim is:

1. Apparatus for converting an oxygen compound of an alkali metal into alkali metal cyanid, which comprises a furnace having therein a continuously downwardly feeding retort in an intermediate portion 125 of which the charge feeding through said retort is subjected to heat treatment, said furnace having means for unequally heating said intermediate portion to develop copious formation of said cyanid only well 130

6
down toward the lower end of said portion, while yet gradually and substantially uniformly heating said charge during its downward travel through said intermediate portion toward said lower end, and provisions for abruptly cooling the cyanized charge directly upon its emergence from said lower end, said provisions including means to introduce a current of nitrogen into said retort for passage upward through said charge.

2. Apparatus for converting an oxygen compound of an alkali metal into alkali metal cyanid, which comprises a gas-fired furnace having therein a continuously downwardly feeding retort in an intermediate portion of which the charge feeding through said retort is subjected to heat treatment, said retort having flame directing means for 10 unequally heating said intermediate portion to develop copious formation of said cyanid only well down toward the lower end of said portion, while yet gradually and substantially uniformly heating said charge during 20 its downward travel through said intermediate portion toward said lower end, and provisions for abruptly cooling the cyanized charge directly upon its emergence from said lower end, said provisions including 25 means to introduce a current of nitrogen into said retort for passage upward through said charge.

3. Apparatus for converting an oxygen compound of an alkali metal into alkali metal cyanid, which comprises a furnace having therein a retort through which the charge under treatment is substantially continuously delivered, means to heat a part of said retort to reaction temperature, means 35 to establish a gaseous reaction-hindering blanket around the charge in one end of said heated part of the retort, and means to introduce a current of nitrogen into said retort for passage through said heated part 40 from the end thereof opposite that afore said toward, said first mentioned end.

4. The combination of a retort in which a reaction is effected to produce a metal cyanid and carbon monoxid, with means to heat said 50 retort, a supplemental body of carbon monoxid gas, means to introduce said gas into said retort at a point in the latter the temperature of which approximates that at which said cyanid forming reaction can 55 occur, means to cause movement of the charge in said retort away from said point toward a second point in said retort, at which cyanid formation normally occurs, means to supply a current of nitrogen sufficient 60 in quantity to sweep away the carbon monoxid entrained in said charge, by the time that it arrives at said second point, and provisions for preserving said cyanid after its formation.

5. In cyanizing apparatus, the combina-

tion of a substantially vertical, continuously feeding retort comprising a plurality of telescoped sections of different diameters, with means to heat an intermediate portion of said retort unequally, the lower 70 end of said portion being more highly heated than the upper end thereof, the section of said retort immediately beneath said lower end being telescoped thereover and constituting a cooling section, and means to 75 supply a current of nitrogen to said cooling section for movement therefrom substantially directly into the hottest part of said retort.

6. In cyanizing apparatus, the combination of a continuously feeding retort with means for passing a current of nitrogen through said retort in a direction opposite to that in which travels the charge fed through said retort, and means for exteriorly heating a portion of said retort to effect cyanization therein, said apparatus having provisions for increasing the rate of flow of said nitrogen during its progress through said exteriorly heated portion and 90 said heating means having provisions to most highly heat said retort where said nitrogen current is flowing relatively slowly therethrough.

7. In cyanizing apparatus, the combination of a furnace comprising a continuously feeding cyanizing retort and means to heat said retort, said heating means having provisions to heat an extended portion of said retort but moderately, and to highly heat 100 a succeeding portion of said retort into which the charge proceeds from said moderately heated portion, said succeeding portion being of less extent than said first mentioned portion, and said retort having a 105 cooling section adjacent said highly heated portion and substantially immediately therebeyond in the direction in which said charge travels, and means to supply free nitrogen to said retort for fixation thereof 110 in said highly heated portion.

8. In cyanizing apparatus, a heated continuously feeding retort, in combination with means to heat said retort and means to supply a gaseous current thereto, capable 115 of promoting a cyanid forming reaction in the charge in said retort, said gaseous current traversing a heated portion of said retort in a direction opposite that in which travels said charge, a gaseous medium which 120 tends to retard said reaction and means for introducing said medium into said retort in the form of a gaseous current which moves oppositely to the first mentioned current, until it is overcome and swept away by said 125 first mentioned current, said gaseous medium establishing an atmosphere unfavorable to cyanid formation at one end of said heated portion.

9. A process of forming alkali metal 130

- cyanid, which comprises subjecting a mass containing carbon, alkali metal carbonate and catalytic material, to heat treatment, while effecting substantially continuous movement of said mass along a determined path, so regulating conditions in said mass during said movement as to preserve said carbonate and substantially prevent formation of said cyanid therefrom, during the greater part of said treatment, relatively suddenly changing said conditions to favor the formation of said cyanid, and substantially directly thereafter cooling the non-gaseous products of said reaction to prevent loss of said cyanid by volatilization.
10. A process of forming alkali metal cyanid, which comprises subjecting a mass containing carbon, alkali metal carbonate and catalytic material, while in the presence of free nitrogen, to heat treatment, while effecting substantially continuous movement of said mass along a determined path, so regulating the temperature of, and the atmosphere around, said mass, during said movement as to preserve said carbonate and substantially prevent formation of said cyanid therefrom, during the greater part of said treatment, relatively suddenly changing the temperature of said mass and the atmosphere therearound, to favor the formation of said cyanid, and substantially directly thereafter cooling the non-gaseous products of said reaction to prevent loss of said cyanid by volatilization.
15. 11. A process of forming alkali metal cyanid, which comprises subjecting a mass containing carbon, alkali metal carbonate and catalytic material, while in the presence of free nitrogen, to heat treatment, while effecting substantially continuous movement of said mass along a determined path, so regulating the temperature of said mass during said movement as to preserve said carbonate and substantially prevent formation of said cyanid therefrom during the greater part of said treatment, relatively suddenly changing said temperature to favor the formation of said cyanid, and substantially directly thereafter cooling the non-gaseous products of said reaction to prevent loss of said cyanid by volatilization.
20. 12. A process of forming alkali metal cyanid, which comprises subjecting a mass containing carbon, alkali metal carbonate and catalytic material, to heat treatment, while effecting substantially continuous movement of said mass along a determined path, so regulating the atmosphere around said mass during said movement as to preserve said carbonate and substantially prevent formation of said cyanid therefrom, during the greater part of said treatment, relatively suddenly changing said atmosphere to favor the formation of said cyanid, and substantially directly thereafter cooling the non-gaseous products of said reaction to prevent loss of said cyanid by volatilization.
25. 13. A process of forming alkali metal cyanid, which comprises subjecting a bulky mass in which is an oxygen compound capable of acting as the source of the alkali metal base of said cyanid, to an atmosphere of nitrogen mixed with carbon monoxid, to preserve said oxygen compound, as such, and prevent its conversion into said cyanid, while gradually and substantially uniformly heating successive portions of said mass at a temperature at which in the presence of pure nitrogen said cyanid would freely form and volatilize, sweeping away said carbon monoxid from said portions successively, by means of a current of nitrogen while further increasing the temperature of said portions successively, to promptly form said cyanid copiously, and substantially at once cooling said portions, successively, as they become highly cyanized, to preserve the cyanid therein and prevent its volatilization.
30. 14. A process of forming alkali metal cyanid, which comprises establishing a downwardly moving column of material containing an oxygen compound capable of acting as the source of the alkali metal base of said cyanid, externally heating said column along a determined length thereof, and effecting a vigorous reaction to convert said oxygen compound to said cyanid in a reaction zone in said column, of but limited extent and short length as compared to the determined length aforesaid, and then promptly cooling the so cyanized material to prevent volatilization of cyanid therefrom, said reaction zone being substantially immediately above the space where said cooling is effected and being established in part by temperature regulation and in part by flowing preheated free nitrogen copiously through said zone to maintain said zone relatively free from carbon monoxid.
35. 15. In a process for fixing atmospheric nitrogen in the form of alkali metal cyanid by reacting with free nitrogen upon a highly porous mixture of carbon, catalytic material and an oxygen compound of said alkali metal, in a downwardly moving column of said mixture which is externally heated to effect said reaction in an extended intermediate portion of said column and then cooled in a lower part of said column,—the improvement which comprises substantially limiting the seat of said reaction to a zone which is relatively shallow in depth as compared to the total length of said externally heated portion, so as to rapidly produce the bulk of the cyanid adjacent said cooled part of the column, and then lowering the temperature of said cyanid, in the upper end of said cooled part,

as rapidly as possible to reduce substantially to a minimum the distillation of said cyanid up into the upper parts of said externally heated portion of said column.

5 16. In a process for fixing atmospheric nitrogen in the form of alkali metal cyanid by reacting with free nitrogen upon a highly porous mixture of carbon, catalytic material and an oxygen compound of said 10 alkali metal, in a downwardly moving column of said mixture which is externally heated to effect said reaction in an extended intermediate portion of said column and then cooled in a lower part of 15 said column,—the improvement which comprises substantially limiting the seat of said reaction to a zone which is relatively shallow in depth as compared to the total length of said externally heated portion, in 20 part at least, by taking advantage of the normally deleterious effect of carbon monoxid upon said cyanid, to suppress cyanid formation except in said zone, said zone being located in said column immediately 25 above said cooled part, and then lowering the temperature of said cyanid sufficiently to substantially prevent distillation of said cyanid.

17. In a process for fixing atmospheric

nitrogen in the form of alkali metal cyanid 30 by reacting with free nitrogen upon a highly porous mixture of carbon, catalytic material and an oxygen compound of said alkali metal, in a downwardly moving column of said mixture which is externally 35 heated to effect said reaction in an extended intermediate portion of said column and then cooled in a lower part of said column,—the improvement which comprises substantially limiting the seat of said reaction to a zone which is relatively shallow 40 in depth as compared to the total length of said externally heated portion, by taking advantage of the normally deleterious effect of carbon monoxid upon said cyanid 45 and by temperature regulation, to suppress cyanid formation except in said zone, said zone being located in said column immediately 50 above said cooled part, and then lowering the temperature of said cyanid sufficiently to substantially prevent distillation of said cyanid.

In testimony whereof I have affixed my signature, in the presence of two witnesses.

CHARLES P. HIDDEN.

Witnesses:

HOWARD C. RIPLEY,
HOWARD F. HYLAND.
